(57) **CLAIM**

I claim the ornamental design for a broom body, as shown and described.

DESCRIPTION

FIG. 1 is a perspective view of a first embodiment of a broom body according to the present invention.

FIG. 2 is a front elevational view of the broom body of FIG. 1.

FIG. 3 is a rear elevational view of the broom body of FIG. 1.

FIG. 4 is a first side elevational view of the broom body of FIG. 1.

FIG. 5 is a second side elevational view of the broom body of FIG. 1.

FIG. 6 is a top plan view of the broom body of FIG. 1.

FIG. 7 is a perspective view of a second embodiment of a broom body according to the present invention.

FIG. 8 is a front elevational view of the broom body of FIG. 7.

FIG. 9 is a rear elevational view of the broom body of FIG. 7.

FIG. 10 is a first side elevational view of the broom body of FIG. 7.

FIG. 11 is a second side elevational view of the broom body of FIG. 7; and,

FIG. 12 is a top plan view of the broom body of FIG. 7.

The broken lines shown in the drawings are for environmental purposes only and form no part of the claimed design.
